UNITED STATES PATENT OFFICE.

ARTHUR A. ROBB, OF AKRON, OHIO, ASSIGNOR TO THE B. F. GOODRICH COMPANY, OF NEW YORK, N. Y., A CORPORATION OF NEW YORK.

DESIGN FOR A CUSHION-TIRE.

59,684.

Specification for Design.

Patented Nov. 15, 1921.

Application filed June 21, 1921. Serial No. 479,387. Term of patent 14 years.

To all whom it may concern:

Be it known that I, ARTHUR A. ROBB, a citizen of the United States, residing at Akron, in the county of Summit and State of Ohio, have invented a new, original, and ornamental Design for a Cushion-Tire, of which the following is a specification, reference being had to the accompanying drawing, forming a part thereof.

The drawing is a perspective view of a cushion tire embodying my design.

I claim:

The ornamental design for a cushion tire as shown.

ARTHUR A. ROBB.
